UNITED STATES PATENT OFFICE.

PHILIP HAAS, OF DAYTON, OHIO.

WALL CLOSET.

Application filed November 14, 1921. Serial No. 514,952.

To all whom it may concern:

Be it known that I, PHILIP HAAS, a citizen of the United States, residing at Dayton, in the county of Montgomery and State of Ohio, have invented certain new and useful Improvements in Wall Closets; and I do hereby declare the following to be a full, clear, and exact description of the invention, such as will enable others skilled 10 in the art to which it appertains to make and use the same.

My invention consists in the novel features hereinafter described, reference being had to the accompanying drawings which 15 show one embodiment of my invention, selected by me for purposes of illustration, and the said invention is fully disclosed in the following description and claims.

In the evolution of bathroom or toilet fixtures, it has become desirable for aesthetic, as well as sanitary, reasons to employ what are termed wall closets, in which the water closet bowl is supported entirely above the floor and all the pipe connections therefrom 20 are carried into the wall and are concealed therein. In the installation of these wall closets a number of problems have presented themselves. In the first place, the bowl must be adequately supported so as to 25 withstand considerable weight, without becoming loose or injuring the wall, or bending, or loosening the pipe connections. Again, variations occur in the thickness of walls in which these closets are installed in 30 different houses or buildings, and the exterior finish of the wall varies according to whether it is finished with plaster suitably decorated, or tiling, or otherwise. Moreover the pipe fittings are usually installed 35 suitably in advance of the plaster work and decorations, while the interior fixtures, such as these wall closets, are installed after the walls have been plastered or tiled, and the exact location of the outer surface of the 40 finished wall is not accurately determined at the time the soil pipes and other pipe connections are installed in the building. Again, in the installation of the vertical soil pipes, for example, slight inaccuracies 45 in the workmanship or in the placing of the closet apertures may readily occur, which

would cause the closets to set inaccurately with respect to the wall, unless suitable provisions were made to compensate for the same, as it is of importance to the finish 55 of the closet that the wall engaging portion of the bowl should fit accurately against the exterior surface of the wall and that the bowl be maintained exactly true.

The object of my invention is to provide 60 means for supporting wall closet bowls from the soil pipe itself and at the same time to provide means for compensating for variations in the thickness of walls in different buildings where these devices are installed, and further to compensate for any irregularities or inaccuracies in the workmanship, 65 in installing the supporting soil pipe line, so that under all circumstances the bowl may be accurately supported in proper position, and with its wall engaging face in absolute alignment with and in contact with the exterior surface of the wall however it may be finished. It is to be further noted that in installing these wall closets the connections which support the porcelain bowl 70 are also relied upon to tighten the joint between the discharge passage of the bowl and the soil pipe, which joint is entirely concealed within the porcelain bowl, and it is 75 difficult for the workman to ascertain that the joint or connection with the soil pipe is tight when he tightens up the supporting devices, and if it should not be tight, leakage and serious injury to the building 80 might result.

My invention also contemplates the employment of a test plate having portions for engaging the devices which support the bowl, and means for compressing and tightening the connection with the soil pipe exactly corresponding to the corresponding parts of the bowl, the plate forming a temporary closure for the bowl connection of the soil pipe and its use enabling the operator 90 to ascertain definitely whether or not the pipe connection will be tight when the bowl is in place and drawn up to the fullest extent by the bowl securing devices, and also whether or not the rear face of 95 the bowl will be exactly flush with the wall. The use of this plate also enables the pre-

liminary testing of the soil pipe line by filling it with water in advance of the installation of the closet bowl and also permitting one or more of the bowls to be installed in the building for use during the completion of the building, or otherwise without installing the entire number required for the building, where this is desirable.

- 10 Referring to the accompanying drawings, Fig. 1 represents a front view of a wall closet and its supporting soil pipe section, the wall of the building being broken away to show the vertical studs and the means 15 for supporting the upper end of the soil pipe section to which the bowl is connected.

Fig. 2 is a side elevation of the same, partly in section.

Fig. 3 is a front elevation of my improved 20 bowl supporting soil pipe section.

Fig. 4 is an enlarged horizontal section showing the soil pipe and its connection with the bowl, the latter being broken away.

Fig. 5 is a similar view showing a modified construction in which the compensating spacing rings are employed to compensate for variations in the thickness of the wall.

Fig. 6 is a view similar to Fig. 5 showing a compensating ring of varying thickness 30 for compensating for inaccuracies in the position of the soil pipe.

Fig. 7 is a front elevation of the test plate and temporary closure.

Fig. 8 is a vertical sectional view of the 35 same.

Fig. 9 is a detail sectional view of one of the compensating rings.

Fig. 10 is a plan view showing the test plate applied to and closing the aperture in 40 the soil pipe, one spacing ring and one compensating ring being shown, parts of the wall and of the soil pipe being shown in section.

Fig. 11 is a sectional view similar to Fig. 45 6, showing the parts illustrated in Fig. 10.

In carrying out my invention I employ a special soil pipe section, indicated at 1, which is provided at its opposite ends with suitable means for engaging adjacent pipe sections 50 forming portions of the soil pipe line of the building. In the present instance the upper end of the soil pipe is provided with a bell 2 and the lower end with the usual spigot 3 for fitting the bell of an adjacent section. At some point between its ends 55 the soil pipe is provided with a lateral aperture, indicated at 4, surrounded by an attaching flange, indicated at 5, which as shown is provided with a plurality of bowl 60 supporting devices, in this instance, threaded studs 6, preferably of brass, which are conveniently threaded throughout their length and screwed into threaded apertures in the flange 5, as shown. The front face of the 65 flange 5 is also provided with a packing re-

cess 7. At a suitable distance above the aperture 4 the pipe section 1 is provided on opposite sides with lateral projecting horizontally disposed supports for engaging apertures in the vertical studs of the wall of the 70 building, for example, which are indicated at 8—8 in Fig. 1. I prefer to provide the pipe section 1 with opposite apertures 9—9

having their axes disposed perpendicularly of the axis of the aperture 4 and into the 75 apertures 9 are screwed sections of pipe, indicated at 10, of suitable diameter, passed through the aperture in the stud provided for that purpose. One of the studs 8 is shown partly in section to illustrate the 80 aperture, indicated at 11, through which the adjacent pipe section 10 passes. If it is desired, one or both of the pipe sections 10 may

be connected by T 12 with a vertical pipe line, indicated at 13, forming part of the ventilating system for the closet trap, and other traps in the building, and the other pipe section 10 may be closed by a suitable cap, as indicated at 14, or if desired, both pipes 10 may be capped, their main function being to support the upper end of the pipe section 1 at a considerable distance above the bowl so as to anchor the upper end of the pipe section and prevent the bowl from tipping forward when exposed to considerable weight or pressure. As the lower end of the soil pipe section 1 is firmly supported in the bell end of the adjacent lower section, 95

the pipe section 1 installed in the manner indicated in Fig. 1, in connection with the 100 studding or other parts of the wall, will form a very stable and unyielding support for the bowl. I do not limit myself to the exact construction illustrated in Fig. 1, as

for example, it is obvious that I may employ 105 in place of the pipe sections 10, solid bars or arms screwed into threaded apertures in the pipe section 1 or otherwise rigidly attached thereto to form the laterally extending anchoring arms for the upper end of the 110 pipe section, and these anchoring arms however made may be otherwise rigidly supported in the wall structure, but in practice I find it extremely convenient to employ the short pipe sections 10 in the manner shown 115

and to anchor them to the wall by simply passing them through suitable apertures in the studding with which the wall will be usually provided. The essential feature of this portion of my invention is the provision 120 of anchoring means for the pipe section, for rigidly securing it to the wall of the building at a point considerably above the point of attachment of the bowl or wall closet.

The closet bowl illustrated at 15, provided 125 with the usual seat 16, and cover 17, is provided with the usual discharge aperture, indicated at 18, surrounding which the bowl is provided with an attaching flange 19, the rear face of which is adapted to fit flush 130

with the face of the wall. In Fig. 4 for example, I have shown, in horizontal section, a simple means of connecting the bowl to the soil pipe section 1, when the soil pipe 5 has been accurately placed in position, and a very thin wall coating is employed, the exterior of the wall surface being substantially flush with the outer face of the flange 5 of the pipe section 1. For effecting the connection 10 between the closet bowl and the lateral discharge aperture 4 of the soil pipe section, I prefer to employ a connecting sleeve, preferably of brass, indicated at 20, which is plain or unthreaded and is provided with a flange 21 engaging the bottom 15 of the packing recess 7, and being of less width than the packing recess, a packing ring, indicated at 22, being employed between the packing recess 7 and a corresponding packing recess, indicated at 23, in the 20 porcelain bowl surrounding the aperture 18 therein.

This connection in its simplest form is illustrated in Fig. 4 of the accompanying drawing on an enlarged scale, and is the construction I prefer to use where the thickness of the wall and the relation of the soil pipe to the outer surface of the wall is as shown in Fig. 4, that is to say, substantially 25 true and flush with the base of the coupling flange 5 surrounding the aperture 4 in the soil pipe.

Where the surface of the wall extends beyond the surface of the flange 5, by reason of the additional thickness of the plastic coating, or by reason of the use of tiling, or by reason of the fact that the soil pipe has been located a little too far away 30 from the plane of the outer surface of the wall, or for any other reason, I may employ the construction illustrated in Fig. 5. In this case I employ the coupling sleeve 20, but instead of placing the flange 21 against the rear face of the packing recess, 35 as shown in Fig. 4, the sleeve is preferably reversed and a packing ring 22^a is interposed between the bevel face of the flange 21 and the packing recess 7. I then place around the sleeve one or more spacing rings 24, as 40 shown in Fig. 5, engaging the flange 21, a sufficient number of spacing rings of the required thickness, or a single ring of the required thickness being employed to bring the rear face of the closet bowl flush with 45 the outer face of the wall and a packing ring 22^b between the spacing rings and the packing recess 23 in the bowl. The spacing rings 24 are preferably soldered or brazed to the sleeve 20 after the required thickness 50 has been determined, as hereinafter described.

In Fig. 6 I have shown another view of this connection between the soil pipe and the bowl, especially designed to illustrate a situation which often arises, in which there is

a slight inaccuracy in the setting of the soil pipe so that the outer face of the coupling flange 5 thereof is not parallel with the outer face of the wall, as clearly shown in Fig. 6. In such case, it is obvious that it would be very difficult to make a tight connection, and at the same time bring the rear face of the closet bowl flush against the outer face of the wall unless some special provision was made for that purpose. To this end I 70 provide one or more compensating spacing rings 25, one of which is illustrated in position in Fig. 6. These compensating spacing rings are so constructed that their opposite faces are disposed at an angle to each other, making the ring of varying thickness throughout its annular extent. One of these rings is shown in detail in Fig. 9, and I may employ more than one if necessary. It will be obvious that by placing one or more 80 of these compensating rings around the sleeve 20, as shown in Fig. 6, and adjusting it, or them, annularly, the variation due to the inaccurate setting of the soil pipe can be readily compensated for so that when the packing rings are drawn up tight, the closet bowl will have its rear face brought flush against the wall, notwithstanding the angular position of the sleeve with respect thereto. The compensating ring or rings 85 25 may be used with or without one or more of the ordinary spacing rings 24 according to the situation, in which this connection is made, and after the exact position of the compensating rings is determined, the compensating and spacing rings are preferably 90 soldered to the sleeve 20.

It will be readily understood that as the packing ring in the porcelain bowl, indicated at 23, is entirely out of sight when the bowl is in place against the wall, it will be extremely difficult for anyone installing one of these wall closets to know whether the joint was sufficiently tight when the bowl had been drawn back by the threaded connection before described, sufficiently far to bring the rear face of the bowl against the wall. Obviously the bowl could not be drawn back any further, and if the joint should not be tight, there would be leakage 105 as soon as the water passed through the joint from the bowl to the soil pipe, which might result in serious injury to the building. I have, therefore, for the purpose of meeting this difficulty, and for other purposes hereinafter referred to, devised a test plate, one embodiment of which is illustrated in Fig. 7 of the accompanying drawings, which will enable an operator in installing these water closets to ascertain before hand whether the joint will be tight when the bowl is drawn to its final position, and is flush with and against the wall. This plate, indicated at 110 26, is provided with a central portion 27, which forms a closure for the aperture 4 115 120 125 130

and is provided at its rear face with a recess 28 to receive the outer end of the sleeve 20, see Figs. 10 and 11, in which I have shown this plate in use in place of the bowl. The 5 plate 26 extends for the most part only a little ways beyond the outer periphery of the recess 28 but is provided with extensions 29 having oval bolt holes 30 therein, and bosses 31 surrounding the bolt holes, the 10 thickness of the plate at the bosses being the same as the thickness of the porcelain flange 19 of the bowl through which the threaded attaching bolts or screws extend. The plate 26 therefore presents in its rear 15 face and its thickness at the bosses, a reproduction of the corresponding portions of the bowl, but as it extends only a short distance from the sleeve, it permits of the observation of the parts which form the joint.

20 After the sleeve 20 is placed in position, the test plate can be applied to the threaded connections and the operator will be able to judge as to the thickness of such spacing 25 rings or compensating rings as may be necessary to make the joint tight, when the rear face of the plate is brought flush with the wall. If necessary the adjacent portions of the wall immediately surrounding the parts can be cut away sufficiently to enable the 30 operator to thoroughly inspect the joint, as the surrounding portions of the wall are to be afterwards completely covered and concealed by the broad rear flange of the closet bowl. The operator will then proceed applying such spacing ring or rings and 35 compensating ring or rings as may be required, placing the packing rings 22^a and 23 in position and adjusting the compensating ring or rings in a circular direction with respect 40 to the sleeve 20, and if necessary with respect to each other, until it appears that when the joint is made tight, the rear face of the plate will be brought against the surface of the wall and in perfect parallelism 45 therewith, notwithstanding any inaccuracy or angularity of the flange 5 of the soil pipe. It is not necessary, however, to leave this matter to conjecture, as the operator can draw up the bolts tight, thereby making a 50 tight joint between the pipe and the test plate, and closing the opening 4 of the soil pipe. It can then be absolutely determined whether or not the rear face of the plate is flush with the wall, and it can also be determined 55 whether or not the joint is tight, because by placing these test plates in all the openings 4 of the soil pipe, intended for different wall closets, the pipe may be filled with water and it can be ascertained positively 60 whether or not the joints are tight. If any joint leaks even slightly, the joint can be separated by the removal of the threaded connection and the test plate and the spacing or compensating rings changed or further 65 adjusted to secure the desired result. If, as

may frequently happen, a considerable space exists between the rear face of the test plate and the flange 5 on the soil pipe, I prefer to provide washers of fibre or metal surrounding the threaded connections illustrated in Fig. 10 at 32, a sufficient number of washers being provided for each of the threaded connections to completely bridge these spaces. After the exact adjustment of the apparatus necessary to produce a tight 70 joint have been determined by the use of the test plate, and when it is desired to install the closet bowl, it is only necessary to remove the test plate, and after soldering the spacing and compensating rings to the sleeve 20 75 in the exact positions to which they have been adjusted, and replacing the parts in exactly the same position, which can be readily accomplished by marking the various parts before disassembling the joint, the 80 closet bowl is placed in position and the threaded connections are drawn up, this time clamping the closet bowl in position, and when the threaded connections have been tightened so as to bring the rear face 85 of the bowl against the wall in the same position occupied by the rear face of the plate 26, the operator will know that the joint is tight. In this connection it is to be noted that the washers 32 will assist the operator in 90 accurately setting the porcelain bowl, as they will prevent him from drawing the nuts or threaded connections down beyond the point permitted by the washers, thus preventing 95 tilting the bowl sideways or putting too great a strain at one point before applying the strain at the other points of connection, which might otherwise occur, and which might result in making the joint imperfect, and also in cracking the porcelain.

100 It is also to be noted that the oval shaped or elongated bolt holes 30 in the test plate will allow for lateral and angular movement of the plate with respect to the threaded connections when the test plate is used to ascertain approximately the position which the rear face of the bowl will occupy and the distance to be filled by the spacing rings or compensating rings, or both.

110 The use of the test plate 26 also serves a further purpose in the installation of these closet bowls. Where the soil pipe line has been installed and the walls completed, as is customary before the installation of the 115 closet bowls, the apertures 4 in the soil pipe at various points in the building, can be closed by means of these test plates, in the manner before described, and if it is desired to install one of the bowls at some 120 point for temporary or immediate use, any one of these plates can be removed and the bowl installed, without installing the other bowls, and the entire system can be operatively employed temporarily, as during 125 130

the construction or finishing of the building, the remaining bowls to be placed in position at a later date when the interior work has progressed.

- 5 It will be seen that in employing the construction herein shown and described, the weight of the bowl and all strains applied thereto will be directly sustained by the soil pipe through the attaching bolts 6 and 10 spacing devices or washers 32, without the possibility of having any strain exerted either upon the wall or upon the sleeve 20, and its packing which make the connection between the pipe and bowl watertight.
- 15 This is possible by reason of the use of a plain unthreaded sleeve (20) and its packing rings and differential spacing devices which permit these parts to be so arranged as to be brought into water-tight condition 20 by the screwing up of the bolts 6 which bring the bowl to its final position flush with the wall but supported independently of it from the soil pipe through the intermediate spacing means between the attaching 25 flanges of the pipe and bowl, while the water connections are entirely relieved of strain.

What I claim and desire to secure by Letters Patent is:—

- 30 1. In a device of the kind described, the combination with a bowl supporting soil pipe section having a lateral aperture, and provided with a vertically disposed attaching flange, and an annular packing recess 35 in the face of said flange, surrounding said aperture, of a wall closet provided with an outlet aperture adapted to register with the lateral aperture in the soil pipe, and having an annular packing recess surrounding 40 said aperture and an attaching flange, an unthreaded sleeve extending through said registering apertures of the pipe and bowl, annularly disposed packing material extending around the exterior of said sleeve, 45 intermediate its ends for effecting a tight joint between said pipe bowl and sleeve, threaded devices connecting the attaching flanges of said pipe section and bowl, and spacing devices between said attaching flanges.
- 50 2. In a device of the kind described the combination with a bowl supporting soil pipe section having a lateral aperture, and provided with a vertically disposed attaching flange, and an annular packing recess 55 in the face of said flange, surrounding said aperture, of a wall closet provided with an outlet aperture adapted to register with the lateral aperture in the soil pipe, and having an annular packing recess surrounding 60 said aperture and an attaching flange, an unthreaded sleeve extending through said registering apertures of the pipe and bowl, annularly disposed packing material extending 65 around the exterior of said sleeve, inter-
- mediate its ends for effecting a tight joint between said pipe bowl and sleeve, said sleeve being provided on its exterior between its ends with an outwardly extending packing engaging flange, threaded connecting devices engaging the attaching flanges of the soil pipe and bowl, and spacing devices between said attaching flanges. 70
3. In a device of the kind described the combination with a bowl supporting soil pipe section having a lateral aperture and provided with a vertically disposed attaching flange, and an annular packing recess in the face of said flange, surrounding said aperture of a wall closet provided with an outlet aperture adapted to register with the lateral aperture in the soil pipe, and having an annular packing recess surrounding said aperture and an attaching flange, an unthreaded sleeve extending through said registering apertures of the pipe and bowl, said sleeve being provided on its exterior with an annular packing engaging flange, an annular packing ring surrounding said sleeve 80 and interposed between said annular flange and the packing recess in said attaching flange on the soil pipe, an annular packing ring engaging the packing recess of the bowl, said ring surrounding the said sleeve and being located between the bowl and the annular flange on said sleeve, threaded connecting devices engaging the attaching flanges of said pipe and bowl, and spacing devices between said attaching flanges. 85
4. In a device of the kind described the combination with a bowl supporting soil pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said 90 aperture and an attaching flange, an unthreaded sleeve extending through said registering apertures of the pipe and bowl, said sleeve being provided on its exterior with an annular packing engaging flange, an annular packing ring surrounding said sleeve and interposed between said annular flange and the packing recess in said attaching flange on the soil pipe, a spacing ring surrounding said sleeve, and located between the said annular flange and the bowl, a packing ring in the packing recess of the bowl surrounding said sleeve, and located between the said packing recess of the bowl and said spacing ring, threaded connecting devices engaging the attaching flanges of said pipe and bowl, and spacing devices between said attaching flanges. 95
5. In a device of the kind described the combination with a bowl supporting soil 100 pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said 105 aperture and an attaching flange, an unthreaded sleeve extending through said registering apertures of the pipe and bowl, said sleeve being provided on its exterior with an annular packing engaging flange, an annular packing ring surrounding said sleeve and interposed between said annular flange and the packing recess in said attaching flange on the soil pipe, a spacing ring surrounding said sleeve, and located between the said annular flange and the bowl, a packing ring in the packing recess of the bowl surrounding said sleeve, and located between the said packing recess of the bowl and said spacing ring, threaded connecting devices engaging the attaching flanges of said pipe and bowl, and spacing devices between said attaching flanges. 110
6. In a device of the kind described the combination with a bowl supporting soil pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said 115 aperture and an attaching flange, an unthreaded sleeve extending through said registering apertures of the pipe and bowl, said sleeve being provided on its exterior with an annular packing engaging flange, an annular packing ring surrounding said sleeve and interposed between said annular flange and the packing recess in said attaching flange on the soil pipe, a spacing ring surrounding said sleeve, and located between the said annular flange and the bowl, a packing ring in the packing recess of the bowl surrounding said sleeve, and located between the said packing recess of the bowl and said spacing ring, threaded connecting devices engaging the attaching flanges of said pipe and bowl, and spacing devices between said attaching flanges. 120
7. In a device of the kind described the combination with a bowl supporting soil pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said 125 aperture and an attaching flange, an unthreaded sleeve extending through said registering apertures of the pipe and bowl, annularly disposed packing material extending around the exterior of said sleeve, inter-

pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said aperture and an attaching flange, an unthreaded sleeve extending through said registering apertures of the pipe and bowl, said sleeve being provided on its exterior with an annular packing engaging flange, an annular packing ring surrounding said sleeve and interposed between said annular flange, and the packing recess in said attaching flange on the soil pipe, a spacing ring surrounding said sleeve, and located between the said annular flange and the bowl, said spacing ring having its opposite faces located in planes at an angle to each other, a packing ring in the packing recess of the bowl, surrounding said sleeve, and located between the bowl and said spacing ring, threaded devices connecting the attaching flanges of said pipe and bowl, and spacing devices between said attaching flanges.

6. In a device of the kind described the combination with a bowl supporting soil pipe section having a lateral aperture and provided with a vertically disposed attaching flange, and an annular packing recess in the face of said flange, surrounding said aperture, of a wall closet provided with an outlet aperture adapted to register with the lateral aperture in the soil pipe, and having an annular packing recess surrounding said aperture and an attaching flange, an unthreaded sleeve extending through said registering apertures of the pipe and bowl, said sleeve being provided on its exterior with an annular packing engaging flange, an annular packing ring surrounding said sleeve, and interposed between said annular flange and the packing recess in said attaching flange on the soil pipe, a plurality of spacing rings surrounding said sleeve, and located between said annular flange and the bowl, certain of said spacing rings having their opposite faces lying in planes at an angle to each other, a packing ring surrounding said sleeve, located in the packing recess of said bowl, and between said packing recess of said spacing rings, threaded devices for connecting the attaching flanges of said pipe and bowl, and spacing devices between said attaching flanges.

7. In a device of the kind described the combination with a vertically supported soil pipe provided with a lateral aperture having a horizontal axis, said pipe being provided with a vertically disposed attaching flange, formed integrally therewith, surrounding said pipe aperture and provided on its face

with an annular packing recess concentric with said aperture, of a bowl provided with a discharge aperture adapted to register with the aperture in the soil pipe, a packing recess surrounding said aperture and an attaching flange surrounding said aperture, a plain unthreaded sleeve having its end portions engaging the apertures of said soil pipe and bowl and provided exteriorly with an annular flange, a packing ring in the packing recess of the soil pipe, surrounding the ring on one side of the said annular flange, a packing ring located in the packing recess of the bowl, surrounding the said sleeve, on the opposite side of said annular flange, and bolts and nuts connecting the attaching flanges of said soil pipe and bowl, and spacing washers between the said attaching flanges located around said bolts for relieving the wall and said sleeve from strain.

8. In a device of the kind described, the combination with a bowl supporting soil pipe section, provided with a lateral aperture, a connecting flange surrounding the same, and threaded connections connected with said flange, of a wall closet provided with an outlet aperture adapted to register with the lateral aperture in the soil pipe section, and having an attaching flange surrounding said aperture and provided with apertures for said threaded connections, a connecting sleeve fitting said apertures, packing rings for said sleeve, and a closing plate having a central portion fitting said sleeve, and lateral flange portions provided with apertures for the passage of said threaded connections, said plate having its rear face, and said flange portions, corresponding with the corresponding portions of the bowl, whereby said plate can be used as a test plate to ascertain the exact position of the rear face of the bowl when in place, and for temporarily closing the bowl engaging aperture in the soil pipe section.

9. In a device of the kind described, the combination with a bowl supporting soil pipe section, provided with a lateral aperture, a connecting flange surrounding the same, and threaded connections connected with said flange, of a wall closet provided with an outlet aperture adapted to register with the lateral aperture in the soil pipe section, and having an attaching flange surrounding said aperture and provided with apertures for said threaded connections, a connecting sleeve fitting said apertures, packing rings for said sleeve, and a closing plate having a central portion for engaging the sleeve and one of said packing rings, and lateral flange portions provided with radial slots for engaging the said threaded connections, spacing rings on said sleeve, certain of said rings having their

opposite faces disposed at an angle to each other, spacing washers on said threaded connections and nuts for engaging the same, said plate having its rear face and said flange portions corresponding with the rear portion of the bowl, whereby said plate may be employed to close said lateral bowl

engaging aperture of the soil pipe section, and may be used as a test plate to insure the alignment of the rear face of the bowl **10** with the wall.

In testimony whereof I affix my signature.

PHILIP HAAS.
